5 Claims. (Cl. 260—683)

This invention relates to the production of unsaturated hydrocarbons from liquid hydrocarbons. More specifically, the present invention is directed to the production of unsaturated hydrocarbons from low and high boiling liquid hydrocarbons while avoiding the formation of carbon black and coke.

It is known to prepare unsaturated hydrocarbons by partial combustion of hydrocarbons, if desired with the supply of steam. The initial materials are introduced into the reaction chamber in the form of vapor or in a finely atomized state, for example through jets. The heat necessary for the cracking is produced either by burning part of the initial material or other combustible substances in the reaction chamber or in a special chamber in front of the same.

It is also known to produce fuel gases by burning hydrocarbons with air or oxygen in a cylindrical combustion chamber, a ring of flame adjacent the wall being produced by tangential introduction of the two reactants at appropriate high speeds. Into this ring, the atomized liquid hydrocarbon is then sprayed axially with the addition of steam. An intensive thorough mixing of the components thereby takes place and the desired cracking reaction occurs.

This method has the disadvantage that, by reason of the sudden mixing of the components, cracking of part of the substances to be cracked may take place at the hot wall of the reaction chamber as a consequence of which carbon black and coke form and may cause difficulties by deposition and stoppage both in the reaction chamber and in the attached apparatus. Moreover, the yield of unsaturated hydrocarbons is diminished by the said formation of carbon black and coke. This disadvantage is especially evident when high boiling hydrocarbons, for example bunker C oils, serve as initial material, because on the one hand these are difficult to atomize and on the other hand they tend in a high degree to form carbon black and coke.

We have now found that the said disadvantages are avoided by introducing the liquid hydrocarbons to be cracked through a tube with a free outlet into the reaction chamber in the neighborhood of the inner wall, and introducing oxygen or oxygen-containing gas, and if desired also superheated steam, combustion gas and/or return gas, tangentially at high speed through a slit near to the said point of introduction. By the speed of the said gas, and owing to the fact that the first part of the reaction chamber, into which the hydrocarbons and the said gas enter, is conically constricted at the end, detachment of the vortex from the wall is avoided. The liquid hydrocarbon is vaporized and partially burnt, and the reaction of the vapors formed is initiated. The further reaction of the initial materials takes place in a second part of the reaction vessel which is cylindrical or advantageously widens like a diffuser and then preferably proceeds cylindrically.

By working in this way, the sudden mixing of the hydrocarbons and oxygen-containing gas, which takes place in the known method and leads to the said disturbances by coke formation, is avoided. The speed which is nec-

2

essary in order to avoid detachment of the vortex of oxygen-containing gas from the inner wall in the first part of the reaction chamber and consequent undesirable rapid mixing with the hydrocarbons may readily be ascertained empirically. The effect of different speeds is clearly shown at temperature measurement points distributed over the length and cross-section of the reaction vessel. It may also be observed by determination of the oxygen content in gas samples withdrawn from different places, as well as by the coke deposits which show clearly at gas speeds which are too slow.

The gas speed of the oxygen-containing gas is always greater than that of the hydrocarbons, preferably more than 80 meters per second, advantageously 100 to 200 meters per second higher than that of the hydrocarbons. There then forms in the neighborhood of the axis of the reaction vessel a region of reduced pressure into which the bulk of the vaporized hydrocarbon is drawn.

The liquid initial material may flow in, like the oxygen-containing gas, tangentially, but it may also be introduced radially or parallel to the axis in the neighborhood of the inner wall of the reaction vessel. The process has the advantage that it is also possible to work up hydrocarbon mixtures of any type, for example light naphtha or distillation residues with a viscosity of 760° centistoke at 100° C. without the formation of coke and carbon black. Since an apparatus for vaporization and atomization is not required, there is thus opened up a new way of cracking high boiling oil residues which are difficult to vaporize or atomize.

The course of the cracking is as follows:

The high speed oxygen-containing gas, if desired mixed with steam, spreads out the liquid hydrocarbon mixture to be cracked as a film-like band on the wall of the chamber and evaporation takes place from this band. The mixture of steam and oxygen rotating along the cylindrical wall produces an axial region of reduced pressure into which the vaporous hydrocarbon is drawn. Along the path through the reaction chamber, thanks to the said constructive features, there takes place with decreasing spin the mixing of oxygen, and possibly steam, with the hydrocarbon so that a progressive partial combustion takes place. The temperature of the reaction mixture accordingly increases on its way through the reaction chamber and does not reach the desired final cracking temperature until the end of the reaction chamber.

FIGURE 1 of the accompanying drawings reproduces the course of the temperature in the reaction chamber. This course in the reaction chamber is readily detectable analytically. In the first third of the reaction chamber there occurs in the zones near the wall mainly oxygen at low initial temperatures. These temperatures slowly rise as the distance from the point of introduction of the gases into the reaction chamber increases, corresponding to the decreasing supply of oxygen. On the other hand, unchanged hydrocarbon is still detectable in the interior. In the mixing zone, in which by reason of the continually declining spin there take place the mixing and reaction of the outer rotating layer of steam and oxygen with the hydrocarbon near to the axis, carbon monoxide, hydrogen, olefins and methane are detectable. In the last quarter of the reaction chamber there is found the uniform final composition of the cracking gas in the zone of uniform temperature. This course also explains why no formation of coke takes place on the walls of the chamber. The hydrocarbons react gradually from the interior outward with the mixture of oxygen and steam which is rapidly rotating along the wall, with continually increasing temperature, so that it is quite impossible for uncracked, readily crackable hydrocarbon vapors to pass through to the hot wall and lead to coke deposition thereon. At the end of the reaction cham-

ber the cracked gas is quenched in known manner with water.

An embodiment of the process according to this invention will now be described by way of example with reference to FIGURE 2 of the accompanying drawings. Into part 1 of a cylindrical reaction vessel which has a conical constriction at its end, a mixture of oxygen and steam is introduced through a slot 3 at a speed of 100 to 200 meters per second from tubes 4 and 5 and a channel 6. Through a tilttable supply pipe 7 which is fixed or capable of adjustment in height and which has a free outlet there flows under a slight excess pressure of 500 to 1000 mm. water column a petroleum fraction of the middle boiling range into the channel 6 and thence into the reaction chamber 1 where it is spread out into a film on the inner wall of the reaction vessel by the kinetic energy of the gaseous or vaporous substance. The oil is vaporized at the wall of the reaction vessel which has been preheated by combustion gases introduced at 9. While a part of the oil vapor is burnt to cover the heat required for cracking, the bulk of the oil vapor passes into the neighborhood of the axis of the reaction vessel.

In order to prevent a sudden intensive mixing of the reactants in part 2 of the reaction vessel, the transition from part 1 to part 2 takes place through a conical intermediate member 10 having such a cone angle that a diminution in the rotational speed of the rotating gas and vapor occurs to the desired extent without a troublesome eddying of the whole mixture. The cone angle preferably does not exceed 10°.

The part 2 of the reaction chamber is made cylindrical. It may, however, be continued wholly or partly conically. The reaction is discontinued in known manner by spraying in cooling water at 11 in order to prevent decomposition of the product.

Part 1 of the reaction chamber is lined with heat-resistant material. It is preferable to arrange on its circumference channels for preheating the oxygen-containing gas. The remainder of the reaction vessel may also be wholly or partly lined with heat-resistant material.

The speed of the gas and vapor introduced into the channel 6 may be adjusted as desired depending on the initial material to be cracked by interchangeable inserts with varying cross sections. It is possible to observe the film formation, ignition and so on through a door 12 at one end of the reaction vessel.

The process is carried out at atmospheric or slightly increased pressure, for example at 2 excess atmospheres; higher pressures may be used, however, and in this case the hydrogenating action of the hydrogen formed in the reaction chamber is promoted. To increase this action, hydrogen or hydrogen-containing gases may also be incorporated.

The cooling of the cracked gas formed is effected in known manner by water, but may also be effected by decompressing the gas in a nozzle or with the utilization of energy.

FIGURE 3 is a cross-sectional view of the apparatus shown in FIGURE 2 taken along a line through points A—A.

The following example will further illustrate this invention but the invention is not restricted to this example.

Example

95 kilograms per hour of a light gasoline with a boiling range up to 105° C. is allowed to flow into a reaction vessel according to FIGURE 2 which has a total length of 2400 mm. and which has in the unconstricted part a diameter of 350 mm. At the same time there are supplied to the reaction vessel per kilogram of light gasoline, 0.282 Nm.³ of oxygen and 0.525 kilogram of steam. The cracking temperature is 725° C. at the end of the reaction chamber. The cracked gas leaving the reaction chamber

is cooled with water. It has the following composition in percent by volume:

2.8 of CO ₂
10.6 of C ₃ H ₆ and higher unsaturated hydrocarbons
5 0.5 of C ₂ H ₂
21.1 of C ₂ H ₄
8.8 of H ₂
33.4 of CO
5.0 of C ₂ H ₆ and higher hydrocarbons
10 17.6 of CH ₄
Traces of O ₂ and N ₂ .

The upper calorific value is 9580 kcals. The total yield of olefins amounts to 0.42 kilogram per kilogram of light gasoline introduced.

We claim:

1. A process for the production of unsaturated hydrocarbons from liquid hydrocarbons which comprises introducing a liquid hydrocarbon through a conduit having a free outlet into a cylindrical reaction vessel in the neighborhood of the inner wall of said vessel; introducing a gas selected from the group consisting of oxygen and oxygen-containing gases tangentially into said vessel through a slot near the point of introduction of said liquid hydrocarbon and at a speed greater than the speed of said liquid hydrocarbon, whereby said hydrocarbon forms a filmlike band of liquid on said wall; rotating said gas along the wall of said vessel at a sufficient speed to prevent a detachment of the vortex from the wall, said rotating gas forming an axial region of reduced pressure in said vessel into which said hydrocarbon in vaporous form is drawn; passing said rotating gas through a conical member having a cone angle of less than 10°, the rotational speed of said gas decreasing as it passes through said conical member, whereby progressive partial combustion of said hydrocarbon takes place; and passing said rotating gas and said vaporous hydrocarbon into a second cylindrical member which is adjacent to said conical member, wherein the reaction is completed.
2. A process for the production of unsaturated hydrocarbons from liquid hydrocarbons which comprises introducing a liquid hydrocarbon through a conduit having a free outlet into a cylindrical reaction vessel in the neighborhood of the inner wall of said vessel; introducing a gas selected from the group consisting of oxygen and oxygen-containing gases tangentially into the first zone of said vessel through a slot near the point of introduction of said liquid hydrocarbon and at a speed greater than the speed of said liquid hydrocarbon, whereby said hydrocarbon forms a filmlike band of liquid on said wall; rotating said gas along the wall of said vessel at a sufficient speed to prevent a detachment of the vortex from the wall, said rotating gas forming an axial region of reduced pressure in said vessel into which said hydrocarbon in vaporous form is drawn; passing said rotating gas and said hydrocarbon vapor through a second zone of said vessel wherein the rotational speed of said gas is gradually decreased and wherein said gas is gradually mixed with said vapor causing a partial combustion of said hydrocarbon vapor; and passing said rotating gas and said hydrocarbon vapor into a third zone of said vessel wherein the reaction is completed.
3. A process for the production of unsaturated hydrocarbons from liquid hydrocarbons which comprises: introducing a liquid hydrocarbon into a cylindrical reaction vessel through a conduit having a free outlet in the neighborhood of the inner wall of said vessel; introducing a gas selected from the group consisting of oxygen and oxygen-containing gases tangentially into said vessel through a conduit having a free outlet near the point of introduction of said liquid hydrocarbon and at a speed substantially greater than the speed of said liquid hydrocarbon, whereby said hydrocarbon forms a filmlike band of liquid on said wall; rotating said gas along the wall of said vessel at a sufficient speed to prevent a detachment of the vortex from the wall, said rotating gas forming an axial region of reduced pressure in said vessel into which said hydrocarbon in vaporous form is drawn; passing said rotating gas and said hydrocarbon vapor through a second zone of said vessel wherein the rotational speed of said gas is gradually decreased and wherein said gas is gradually mixed with said vapor causing a partial combustion of said hydrocarbon vapor; and passing said rotating gas and said hydrocarbon vapor into a third zone of said vessel wherein the reaction is completed.

ment of the vortex from the wall in a first zone of said vessel, said rotating gas forming an axial region of reduced pressure in said vessel; gradually vaporizing said hydrocarbon as said filmlike band of liquid hydrocarbon moves through said vessel, whereby said hydrocarbon vapor is drawn into said axial region of reduced pressure; passing said rotating gas and said hydrocarbon vapor into a second zone of said vessel wherein the rotational speed of said gas is gradually decreased and wherein said gas is gradually mixed with said vapor causing a partial combustion of said hydrocarbon vapor; and thereafter passing said rotating gas and said hydrocarbon vapor into a third zone of said vessel wherein the reaction is completed.

4. A process as in claim 3 wherein said gas is introduced into said vessel at a speed that is more than 80

10

15

meters per second faster than the speed at which the said liquid hydrocarbon is introduced into said vessel.

5. A process as in claim 3 wherein said gas is introduced into said vessel at a speed that is from about 100 to about 200 meters per second faster than the speed at which the said liquid hydrocarbon is introduced into said vessel.
